(57) **CLAIM**

The ornamental design for the sunglow teardrop solar light, as shown and described.

DESCRIPTION

FIG. 1 is a perspective view of a sunglow teardrop solar light in accordance with my invention;

FIG. 2 is a top view of the sunglow teardrop solar light shown in FIG. 1;

FIG. 3 is a bottom view of the sunglow teardrop solar light shown in FIG. 1;

FIG. 4 is a right side elevation of the sunglow teardrop solar light shown in FIG. 1; and,

FIG. 5 is a corner elevation of the sunglow teardrop solar light shown in FIG. 1.
